CLAIM

The ornamental design for an applicator assembly as shown and described.

DESCRIPTION

FIG. 1 is a perspective view of an applicator assembly according to an embodiment;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

In the drawings, the broken lines depict portions of the applicator assembly that form no part of the claimed design.

1 Claim, 7 Drawing Sheets
